FEELER MECHANISM FOR LOOMS.

1,369,487.

Specification of Letters Patent. Patented Feb. 22, 1921.

Application filed January 30, 1920. Serial No. 355,065.

To all whom it may concern:

Be it known that I, MELVIN L. STONE, a citizen of the United States, and a resident of Lawrence, in the county of Essex and State of Massachusetts, have invented an Improvement in Feeler Mechanisms for Looms, of which the following description, in connection with the accompanying drawings, is a specification, like characters on the drawings representing like parts.

This invention relates to feeler mechanisms for looms whereby the filling in the shuttle is replenished before complete exhaustion.

Various forms of feeler mechanisms have heretofore been suggested, and among these are those known as "mechanical feelers" and those known as "magnetic or electric feelers." The present invention has more special reference to feelers of the latter type and has for its object the production of a feeler mechanism which shall be sensitive to the presence or absence of filling in the shuttle and, upon substantial exhaustion of the filling, will set in action a train of mechanism to effect replenishment of filling.

In the present invention the magnetic feeler is mounted upon a feeler carrier for movement therewith toward and from the front of the loom and also for movement relative thereto in a rearwardly direction under the attractive force of a metal member carried by the lay as it retreats after a detecting beat. The magnetic feeler and the feeler carrier are held in normally associated relation under the action of a suitable yielding means, such as a spring, but with permissive movement for the magnetic feeler to slide rearwardly on the feeler carrier when the latter has returned to its rearward position as the lay goes back after a detecting beat. Associated with the feeler carrier is an actuator which is held in a normally inoperative position by the magnetic feeler so long as the feeler and the feeler carrier on which it is mounted remain in normal position, but when the magnetic feeler is moved relatively to the feeler carrier, and their position is thereby changed or rendered abnormal, the actuator sets in operation a train of mechanism for effecting replenishment of filling.

In the accompanying drawings, which show one good practical form of the invention:

Figure 1 is a plan view of the feeler side of a loom equipped with the present invention, some of the parts being omitted for clearness of illustration;

Fig. 2 is a cross section on the line 2—2 of Fig. 1 showing the action of the feeler mechanism when the filling has been substantially exhausted on a detecting beat and the lay moves backwardly;

Fig. 3 is a detached perspective detail showing more particularly the relation of the actuator, the magnetic feeler, and the feeler carrier or slide;

Fig. 4 is a plan view partly in section showing details of construction.

The loom frame 1 has mounted thereon the transverse or rock shaft 2, Fig. 1, from which rises the arm 3 having pivotally connected thereto the latch or arm 4, the rear end portion of which is adapted to be engaged by an operating member 5 and pushed forwardly to rock the rock shaft 2 when filling is to be replenished. The operating member 5 may be any suitable moving part of the loom, and as usual in this type of looms it has an arm connected to the cam follower.

Pivots mounted on the loom frame or a bracket 6 rising therefrom, is the transmitter 7, one end of which at 8 underlies the latch 4 and the other end 9 of which is under control of the actuator, as will be presently described, the construction being such that when the transmitter 7 is rocked on its support, the end 8 may be lifted to place the end of the latch 4 in the path of movement of the operating member 5 to effect replenishment of filling.

Secured to the loom frame or a bracket connected therewith, is the feeler stand 10 which, in the present instance, constitutes the support for the feeler carrier. The feeler carrier 11 is formed as a plate at its rear end portion and extends forwardly into the feeler stand 10 where it is surrounded by a spring 12 interposed between the front end portion 13 of the feeler stand and a shoulder 14 on the feeler carrier, the construction being such that the feeler car-

rier will be normally maintained in its rearward position but with permissive movement frontwardly.

5 Mounted for sliding movement on the feeler carrier 11 is the magnetic feeler 15. In the present instance of the invention the magnetic feeler 15 is mounted in a guideway formed longitudinally in the feeler carrier 11 and at its rear portion a plate 16
10 is secured to the feeler carrier 11 to insure that the magnetic feeler 15 be retained upon the feeler carrier as it is reciprocated backward and forward. The described means is an efficient and convenient form of mechanism but obviously the magnetic feeler 15 might be otherwise mounted for sliding movement toward and from the front of the loom on and relative to the feeler carrier 11.

20 The feeler carrier 11 is slotted at 17 and a spring 18 has one end secured at 19 to the feeler carrier and the other end is secured to the front end portion of the magnetic feeler, the construction being such that the spring 18 normally acts to maintain the magnetic feeler 15 in its normal frontward position relative to the feeler carrier 11. A stop shoulder 20 formed on the feeler carrier, is adapted to be engaged by the rear end portion of the magnetic feeler and limit its frontward movement. Any other form of stop might be employed for this purpose. The rear end surface 21 of the feeler carrier, and the rear end surface 22 of the magnetic feeler, are preferably in the same plane and occupy this position during normal operation of the loom when a working supply of filling is present in the shuttle.

40 Rising from the feeler carrier 11 are the brackets 23 in which is mounted the stud 24 carrying the actuator 25. The hub portion 26 of the actuator is mounted on the stud or shaft 24 for rocking movement, and is normally under the action of a spring 27 tending 45 to turn the actuator in a downward direction, viewing Fig. 2. The spring 27 may have one end secured to the hub 26 as indicated in Fig. 4 and the other end secured to the brackets or lugs 23, and two of these 50 springs may be used, if desired, as indicated in Fig. 4, the construction being such that the spring or springs normally act upon the actuator to turn it in a downward direction, viewing Fig. 2.

55 Extending downwardly from the hub of the actuator 25, is the toe 28, the lower end portion of which is adapted to rest upon a projection 29 formed on the magnetic feeler, when said feeler is in its frontward or normal position relative to the feeler carrier, as indicated by dotted lines in Fig. 2.

The actuator 25 is preferably formed with the slot 30 which, when the actuator is in its normal inoperative position, extends substantially in a horizontal direction, and into

the slot 30 of the actuator 25 extends the end 9 of the transmitter.

The lay 31 is or may be of the usual construction and be provided with the shuttle box 32 into which the shuttle 33 is picked. 70 The shuttle 33 has the usual bobbin holding jaws 34 for holding a bobbin or filling carrier 35 which may be of the usual construction, except as will presently appear.

The front wall of the shuttle box is provided with an opening 36 and an adjacent wall of the shuttle is provided with an opening 37 which substantially registers with the opening 36 in the shuttle box when the shuttle 33 is properly positioned in the detecting 75 box, the construction being such that the feeler may extend through the wall of the shuttle box and shuttle and feel for the filling on a detecting beat.

80 The filling carrier or bobbin 35 has mounted thereon a metal member for coöperating with the magnetic feeler when the filling in the shuttle has been substantially exhausted and to cause rearward movement of the magnetic feeler as the lay moves back on a detecting beat.

85 In the present instance of the invention the metal for coöperating with the magnetic feeler member, consists of a plurality of rings or spirals 38 and, in case the series or 90 plurality of rings or spirals are formed in one piece, as is a convenient construction, the ends of the piece may be properly secured to the filling carrier, as at 39 and 40. By having the spirals or rings 38 extend in a series 95 or in plural number longitudinally of the filling carrier, one or more of the rings or spirals will be presented to the end 22 of the magnetic feeler when the filling is substantially exhausted, even though the shuttle may 100 not have been properly positioned in the box.

105 It will be obvious, of course, that the rings or spirals 38 may be variously formed, the purpose of these parts being to provide a metal contact for the end of the permanent 110 magnet 15 which constitutes the feeler.

115 During the operation of the loom when a working supply of filling is present in the shuttle on a detecting beat, the feeler carrier and magnetic feeler will be moved frontwardly in unison by the mass of filling on the carrier, and as the lay goes back the normal position of the feeler carrier and magnetic feeler will remain undisturbed. Since the actuator 25 is carried by the feeler carrier, the end of the toe 28 will continue to rest upon the projection 29 of the magnetic feeler and the end 9 of the transmitter 7 will not be disturbed as the actuator 25 moves frontwardly and backwardly with the feeler carrier. When, however, the filling has become substantially exhausted on a detecting beat, the end 22 of the magnetic feeler will contact with one or more of the rings or spirals 38 on the filling carrier, and, as the 120 125 130

lay goes back, the attraction between the rings and magnet will cause the latter to travel backwardly with the lay even after the feeler carrier 11 has reached the limit of 5 its rearward movement. The relative movement of the magnetic feeler and feeler carrier thus induced causes the projection 29 to be moved from its dotted to its full line position, Fig. 2, thereby permitting the actuator 25 to turn from its dotted to its full 10 line position, rock the transmitter 7 and cause the end of the latch 4 to be positioned in the path of the operating member 5 to effect replenishment of filling.

15 Claims:

1. In a feeler mechanism, the combination of a feeler slide mounted for movement toward and from the front of the loom, a magnetic feeler movably mounted on the slide, 20 a spring normally acting to hold the feeler in its frontward position on the slide, an actuator carried by the feeler slide and normally maintained in a predetermined position by the frontward position of the magnetic feeler and permitted to move to an 25 abnormal position when the magnetic feeler is moved rearwardly from its normal position on the slide, and a transmitter operated by the actuator for effecting replenishment 30 of filling.

2. In a feeler mechanism, the combination of a feeler stand, a feeler slide mounted for movement toward and from the front of the loom, a magnetic feeler movable with and 35 relative to the slide, yielding means for establishing a normal relation between the feeler slide and feeler, an actuator controlled by the magnetic feeler, a shuttle containing a bobbin having a part to coact with the 40 magnetic feeler, and means for replenishing filling when the magnetic feeler is moved rearwardly relative to the slide as the shuttle goes back on a detecting beat.

3. In a feeler mechanism for looms, the 45 combination of a feeler slide mounted for movement toward and from the front of the loom, a spring normally acting to hold the slide in rearward position, a magnetic feeler mounted on the slide for movement rearwardly with and relative thereto, a shuttle 50 having a bobbin provided with a metal part to contact with the feeler on a detecting beat when filling is substantially exhausted and effect movement of the feeler rearwardly 55 relative to the feeler slide after the slide has reached its rearward position and as the shuttle goes back on a detecting beat, and means controlled by the feeler for effecting replenishment of filling.

60 4. In a feeler mechanism for looms, the combination of a feeler slide mounted for movement toward and from the front of the loom, a spring normally acting to hold the slide in rearward position, a magnetic feeler 65 mounted on the slide for movement rear-

wardly with and relative thereto, a shuttle having a bobbin provided with a metal part to contact with the feeler on a detecting beat when filling is substantially exhausted and move the feeler rearwardly relative to the 70 feeler slide as the shuttle goes back on a detecting beat, an actuator, and means controlled by rearward movement of the magnetic feeler relative to the feeler slide for effecting replenishment of filling. 75

5. In a feeler mechanism for looms, the combination of a magnetic feeler, a feeler carrier mounted for movement toward and from the front of the loom, on which the feeler is mounted for movement with and 80 relative to the carrier, an actuator on the feeler carrier which is maintained in normal inoperative position by the magnetic feeler until the latter is moved rearwardly relative to the feeler carrier, and a shuttle having a 85 bobbin provided with a metal piece to effect movement of the magnetic feeler rearwardly relative to the feeler carrier as the shuttle goes back on a detecting beat when the filling is substantially exhausted. 90

6. In a feeler mechanism for looms, the combination of a magnetic feeler, a feeler carrier mounted for movement toward and from the front of the loom and on which the magnetic feeler is mounted for movement 95 with and relative to the carrier, an actuator which is maintained in a normal inoperative position on the carrier by the magnetic feeler until the latter is moved rearwardly relative to the feeler carrier, and a shuttle 100 having a bobbin provided with a plurality of metal coils one or more of which may be engaged by the magnetic feeler when the filling is substantially exhausted on a detecting beat to effect rearward movement of the 105 feeler relative to the carrier as the shuttle goes back.

7. In a feeler mechanism for looms, the combination of a feeler carrier mounted for movement toward and from the front of the 110 loom, a magnetic feeler mounted on the feeler carrier for rearward movement relative to the carrier, a spring between the feeler and feeler carrier normally acting to hold the feeler in a normal frontward position on the carrier, and means for effecting replenishment of filling when the magnetic feeler is moved rearwardly on the feeler carrier on a detecting beat. 115

8. In a feeler mechanism for looms, the 120 combination of a feeler carrier mounted for movement toward and from the front of the loom, a magnetic feeler mounted on the feeler carrier for rearward movement relative to the carrier, a spring normally acting 125 to hold the feeler in a normal frontward position on the carrier, an actuator mounted on the feeler carrier and held in an inoperative position by the magnetic feeler until the feeler is moved rearwardly on the carrier, 130

and means under control of the actuator for effecting replenishment of filling.

9. In a feeler mechanism for looms, the combination of a feeler carrier mounted for movement upon a detecting beat toward the front of the loom, a magnetic feeler mounted on the feeler carrier for rearward movement relative to the carrier, a spring normally holding the feeler in its front position relative to the feeler carrier, an actuator held in an inoperative position by the magnetic feeler until the feeler is moved rearwardly relative to the carrier, and means controlled by the actuator for effecting replenishment of filling.

10. In a feeler mechanism for looms, the combination of a feeler carrier mounted for movement upon a detecting beat toward the front of the loom, a magnetic feeler mounted on the feeler carrier for rearward movement relative to the carrier, a spring normally holding the feeler in its front position relative to the feeler carrier, an actuator having a part which rests upon the feeler when the latter is in its front position on the feeler carrier and is freed to move downward by rearward movement of the feeler, said feeler operable upon movement to its front position to restore the actuator to its raised position, and means controlled by the actuator for effecting replenishment of filling.

11. In a feeler mechanism for looms, the

combination of a feeler carrier mounted for movement upon a detecting beat toward the front of the loom, a magnetic feeler mounted on the feeler carrier for rearward movement relative to the carrier, a spring normally holding the feeler in its front position relative to the feeler carrier, an actuator mounted to be controlled in its position by movement of the feeler toward and from the front of the loom upon its carrier, and means controlled by the actuator for effecting replenishment of filling.

12. In a feeler mechanism for looms, the combination of a feeler carrier which is mounted for movement toward and from the front of the loom, a magnetic feeler which is mounted on the feeler carrier, a spring which normally acts to hold the feeler in a frontward position relative to the feeler carrier with permissive movement rearwardly relative to the feeler carrier when the filling is substantially exhausted on a detecting beat, an actuator, and interengaging parts on the feeler and the actuator which permit movement of the actuator into a position to effect replenishment of filling only when the feeler is moved rearwardly relative to the feeler carrier on a detecting beat.

In testimony whereof, I have signed my name to this specification.

MELVIN L. STONE.
